UNITED STATES PATENT OFFICE.

LEWIS A. HAINES, OF COLUMBUS, OHIO.

IGNITION FOR COMBUSTION-CHAMBERS.

1,284,096.

Specification of Letters Patent.

Patented Nov. 5, 1918.

Application filed October 1, 1917. Serial No. 194,193.

To all whom it may concern:

Be it known that I, LEWIS A. HAINES, a citizen of the United States, residing at Columbus, in the county of Franklin and State 5 of Ohio, have invented new and useful Improvements in Direct Electric Ignition for Combustion-Chambers for Gas-Turbines, of which the following is a specification.

This invention relates to electric ignition 10 means for the combustion chambers of gas turbines, and consists of an improvement on the ignition means and correlative parts of the cylinders and combustion chambers disclosed by my U. S. Patents Nos. 1,219,297 15 and 1,219,298 granted March 13, 1917. In the said patents, the cylinders and reciprocating pistons therein are disposed around a drive or turbine shaft and automatically operate in succession and in varied numbers 20 to compress and ignite charges of an explosive motive agent and deliver the exploded and highly heated charges to rotors or turbine devices for generating power and simultaneously operating the active parts of 25 the turbine or motor as a whole to control the supply of the motive agent to the cylinders and pistons, the regular reciprocation of said pistons and the admission to the compression and ignition chambers of charges 30 of scavenging air which also serve to cool the heated parts of the turbine. In said patents also, the ignition and combustion of the compressed motive agent is produced by means exterior of the combustion chambers 35 at points distant from the outlets to the rotor or turbine device with a certain delay in the release and a deterioration of the burned motive agent and its effectiveness as an actuating medium relatively to the said rotor or turbine device. In the present improvement the ignition of the charges of 40 motive agent takes place through the operation of means located directly in the compression chambers of the reciprocating pistons subsequent to and during the retention 45 of the charges under maximum compression and also at a time when the chambers are adjacent to the outlets and when the burned motive agent charges have the highest degree of efficiency as actuating means for the 50 rotor or turbine device with which they are intended to cooperate. By the improved ignition means also the firing of the charges of the motive agent occurs with certainty 55 and surely by reason of the fact that the

sparks are produced within the compressed charges.

One very effective and practical structure embodying the features of the invention is shown in the accompanying drawings, and 60 therein:

Figure 1 is a cross section through a group of cylinders, pistons, drive shaft and other correlated parts of a gas turbine, showing the features of the present invention em- 65 bodied therein.

Fig. 2 is a slightly enlarged sectional view of one of the cylinders and pistons and intimately related parts thereof, showing the piston at the full limit of its instroke and in 70 a position to discharge the burned motive agent from the compression chamber thereof.

Fig. 3 is a view similar to Fig. 2 showing the piston at the full limit of its outstroke and the chamber thereof in position to receive a charge of the motive agent. 75

Fig. 4 is an elevation of a portion of one of the cylinder inlet valves and operating means for opening the valve at intervals.

The numeral 5 designates a turbine or 80 main driving shaft around which a series of cylinders 6 and pistons 7 are located, the pistons being operatively connected to the shaft, as shown by Fig. 1, and similarly to the pistons shown in my patents aforesaid 85 and, therefore, this known piston connection need not be further described as it forms no part of the present invention. The cylinders 6 have outer heads 8 secured thereto and fully open inner end 10. The cylinders 90 6 and their heads 8 also have water jackets 9 which will be provided with a suitable water circulating means. Each head has a central open space or bore 11 extending fully therethrough, and around the inner portion 95 of said space or bore is a motive agent receiving chamber 12 having an inner terminating valve seat 13. A valve 14 is mounted to operate relatively to the seat 13 to control communication between the chamber 12 and the interior of the cylinder 6. This valve 14 has a tubular stem 15 which has a close sliding fit in the space or bore 11 of the head 8, the valve being centrally bored, as at 16. To the outer end of the valve stem 15 a coupling head 17 is fixed, preferably by a separable screw thread connection, as shown, and the free end of a rocking lever 18 is movably attached to the said head 17 for imparting to the valve stem 15 and valve

14 timed interval reciprocating movements to alternately open and close said valve and thereby regularly charge the cylinder 6 with the motive agent. The lever 18 is movably held on a fulcrum support 19 which in turn will be suitably swiveled or mounted to move on a part of the turbine casing as in my prior patented structures hereinbefore noted. The end of the rocking lever 18 opposite that attached to the coupling head 17 is engaged by a push-rod 20 arranged and actuated similarly to the corresponding rod shown and described in my Patent No. 1,219,297.

15 Within the tubular valve stem 15 a tubular insulator 21 is fixed to move therewith, said insulator being formed of porcelain or other suitable material and provided with an outer hemi-spherical closed head 22 and an inner open end 23. Within the insulator 21 is a tubular conductor 24 having its inner surface flush with the similar surface of said insulator, the conductor 24 being preferably set in an annular recess 25 of the insulator.

20 The conductor is a current gathering and storing medium and is fully open at both ends, and between the inner ends of the insulator 21 and conductor 24 and the body of the valve 14 around the bore 16 where an annular shoulder 26 is formed an insulating washer 27 is interposed and provides a tight non-leakable electric joint with the said adjacent parts. Near the outer extremity of the insulator, metal or other conducting contacts 28 are set in diametrically opposite portions thereof and expand through openings 29 formed in the valve stem 15. The contacts 28 are fully in engagement with the conductor 24 and continually bearing there-

25 against are the inner reduced ends of transmission electrodes 30 of carbon or other suitable material and movably held in tubular carriers 31 of non-conducting material. The carriers 31 are materially longer than the electrodes 30, and between the outer ends of the latter and an interiorly formed annular shoulder 32 of the carriers springs 33 are mounted and have their respective terminals engaging the said outer ends of the electrodes 30 and the heads 34 of bolts or pins 35 extending outwardly through the carriers and conducting binding collars 36 held by nuts 37 against the outer ends of said carriers. The carriers 31 are mounted in sockets 38 exteriorly screw-threaded to engage laterally projecting seats 39 forming portions of each head 8, the sockets having stop flanges 40 to bear against the outer margins or edges of the seats. The carriers 31 are held in fixed adjustable positions in the sockets 38 by set nuts 41 which engage the outwardly projecting threaded extremities of the said sockets and annular flanges 42 of the carriers. It will be seen that the electrodes 30 are held by insulating means and

have a yielding and self-adjusting movement relatively to the contacts 28 owing to the interposed springs 33 which always insure a positive and reliable engagement of the electrodes 30 with the contacts 28, and especially 70 in view of the inner reduced ends or points of said contacts. If vibration should affect the electrodes 30 and cause them to have a tendency to move or jump away from the contacts 28, the springs 33 will immediately 75 restore the engagement of the electrodes with the contacts. Wires or conductors 43 are attached to the collars 36 and may run from a magneto and battery, a battery alone, or any other source of electrical generation. The 80 current passes from the collars 36 by way of the bolts or pins 35 to the springs 33 and thence to the electrodes 30 which in turn transmit the current to the contacts 28 to electrically charge or saturate the tubular 85 conductor 24.

Each piston 7 has a compression chamber 44 adjacent to its outer extremity, the latter having a funnel-shaped extension 45 connected thereto leading to said chamber and 90 provided with an inner valve seat 46 with which a valve 47 has movable association. The peripheral edge 48 of the valve 47 and the valve seat or edge 46 are so formed that the valve will close against said seat in an 95 outward direction, the valve forming a part of the outer wall or top of the chamber 44. The valve 47 has a stem 50 projecting outwardly therefrom and slidably through the bore 16 of the valve 14 and in the tubular conductor 24. The stem 50 is of metal and tubular, and between the inner end thereof and the valve 47 an insulating ring 49 is mounted to prevent transmission and leakage of the electric current at this point of 100 jointure of the said valve and its stem. A porcelain or other non-conducting tubular inclosure or plug 51 is inserted in the valve stem 50, terminating short of the outer end of said stem where a transmission head 52 is 105 provided. The plug 51 extends through the valve 47 and is shouldered against the inner side around the center of said valve, as at 53, and into an inwardly projecting tubular stop 54 forming part of said valve and carrying 110 opposed inwardly extending sparking terminals or pins 55 having a ground connection through the valve 47, extension 45, piston 7, cylinder 6 and the turbine casing. Extending centrally through and secured in the 115 head 52 of the stem 50 and plug 51 is a conducting rod 56 which projects inwardly beyond the inner end of the said plug and into the center of the tubular stop 54 and serves as the electrically active sparking medium 120 relatively to the terminals, pins or points 55, and whereby an ignition means is located directly in the compression chamber of the piston. The stop 54 of the valve 47 is disposed opposite and is adapted to contact 125 130

with a corresponding stop 57 at the inner wall of the chamber 44 to limit the inward movement of the said valve into the chamber and provide for quicker closing action of the 5 valve in a manner more fully hereinafter explained. Each cylinder and piston of the group of these devices shown will be similarly constructed and equipped with the electric current conveying and transmission devices hereinbefore described and operating at proper intervals or times relatively to each cylinder and piston.

The chambers 12 will be supplied with the motive agent in proper mixture as in my 15 patents aforesaid, and the release or exhaust of the burned motive agent is effected through outlets 58 in the chamber walls and adapted to register with similar outlets 59 through the cylinder walls, said outlets in 20 the complete turbine structure opening into ducts leading to rotors or turbine devices as shown by my patents herein noted. In this instance also air under pressure from a suitable source is admitted into the cylinders 6 25 immediately subsequent to the initiation and discharge of the motive agent to scavenge the cylinders and also to cool the heated parts of the turbine, such as the cylinders, pistons, turbine blades, and the connections and 30 ducts. The admission of this air is through a port 60 having a valve 61 operated at intervals between the charging of the chambers 44 and discharge of the burned motive agent from said chambers in a manner similar 35 to the air admission controlling valve of my aforesaid patents. The motive agent mixture is regularly supplied to the chamber 12 in the head 8 of each cylinder at proper intervals and the valve 14 is also opened at 40 corresponding intervals after the charge has been received in said chamber and the supply thereto cut off. The valve 14 is opened to admit the charge from the chamber 12 in the cylinder 6 by operation of the 45 stem 15 through the medium of the mechanism hereinbefore described, all of the movable parts acting with timed movements without interference. The charging of the chamber 44 of the piston 7 ensues during 50 the outstroke of said piston and subsequent to the full discharge of a burned charge from said chamber 44, and also after the cylinders 6 and said chamber 44 having been fully scavenged by the air under pressure admitted to the cylinder and chamber just as 55 the piston starts on its outstroke. As the piston starts on its outstroke, through the operation of the connection therefor relatively to the shaft 5 from the position shown by Fig. 60 2 sufficient inward force is exerted on the stem 50 by reason of its close fitting engagement with the tubular conductor 24 and also the valve 47 to open the latter valve while the piston continues to move outwardly and the air admitted to the cylinder passes into the

chamber 44 and escapes through the outlets 58 before the piston moves far enough to disengage the outlets 58 therefrom from the cylinder outlets 59. The air having performed its function and escaped, the valve 14 is 70 opened at the proper interval to admit a charge of motive agent from the chamber 12 into the cylinder while the piston continues to move outwardly and the valve 47 remains open, and after the motive agent 75 charge is admitted into the cylinder in suitable predetermined volumes the valve 14 is closed and the piston continues to move outwardly and the motive agent is forced into the chamber 44 under pressure. The 80 charge in the chamber 44 causes the valve 47 to close when the pressure of said charge reaches a degree sufficient to overcome all mechanical resistances to such valve closure, and when the piston reaches the limit of its 85 outer stroke, as shown by Fig. 3, the valve 47 will have been tightly closed and will so remain during the full instroke of said piston. During the inward movement of the motive agent charged piston, the conductor 90 95 24 is electrically charged, the stem 50 of the valve 47 taking up and conveying the electricity or current from the said conductor, during movement of the stem in the conductor, to the conducting rod 56 from whence it is discharged relatively to the pins or points 55 to produce the ignition spark directly in the compression chamber 44 of the piston. By means of suitable timing mechanism, this ignition spark will be 100 produced by the means just specified at such intervals as will be most effective in igniting the charge of motive agent in the chamber 44. The ignition of the motive agent in the chamber 44 will take place when the piston 105 is far enough out from the cylinder outlets 59 to permit the confined motive agent charge to be completely burned prior to the registration of the outlets 58 of the chamber 44 with the cylinder outlets 59. 110 It will be understood that the sparking between the inner end of the rod 56 and the terminals, pins or points 55 will be effected by the action of the timer that will be included in the circuit with the wires 43 while 115 the several insulating or non-conducting elements are in adjacent relationship or in such positions as to defeat any possibility of a short circuit current ensuing, and, preferably, this sparking or ignition will take 120 place just at or immediately following the full outstroke of the pistons. In the arrangement shown, the insulating washers or collars 27 and 49 are contiguous when each piston is at the limit of its outstroke 125 and, hence, there could be no short circuit of the current possible and prevention of the short circuit would ensue for some little time during the inward movement of the piston from its full outstroke position or 130

so long as the said insulating washers or collars were in such adjacency as to prevent exposure of the metal parts to the stem 50. It will also be understood that the moment 5 at which the sparking and ignition is effected with relation to each piston may be obviously modified by changing the position of the insulating devices just explained. The purpose of igniting the charge in each 10 piston at some part of the outstroke or adjacent to the limit of the outstroke thereof is to effect a thorough burning of the charge within the piston chamber before the charge is liberated through the outlets 59 and then 15 to the blades of the turbine. When this outlet registration does ensue, the burned motive agent charge instantly discharges to the rotor or turbine device and the cylinder 6 and chamber 44 are then promptly scavenged or cleaned by a charge of air, as hereinbefore explained. A similar operation will be effected in all the cylinders and pistons at 20 regular intervals, or, in only a part of the cylinders and pistons in accordance with the load on the turbine, as clearly described in 25 my patents herein noted. The cylinder and piston operations above described will also be effected in regular sequence and the shaft 5 will be rotated and have all of the driving 30 power of the working cylinders and pistons imposed thereon and taken up thereby for transmission to and use in actuating various mechanisms.

What is claimed is:

- 35 1. A cylinder for a gas turbine having a reciprocating piston therein provided with a compression chamber for a motive agent provided with an automatically opening and closing means, ignition means having sparking components located directly in and movable with said chamber, and driven means to which the piston is connected.
- 40 2. A cylinder for a gas turbine having a reciprocating piston provided with a compression chamber for a motive agent, ignition means having sparking components located directly in said chamber and movable with the latter and the piston, and driven means to which the piston is connected.
- 45 3. A cylinder for a gas turbine having a reciprocating member provided with a compression chamber for a motive agent, and ignition means having sparking components located directly in said chamber and movable therewith.
- 50 4. A cylinder for a gas turbine having a reciprocating piston provided with a compression chamber for a motive agent, ignition means comprising an electrical accumulating device and a conducting means movable in the 55 said accumulating device and in part extending into the compression chamber, the said chamber also having sparking devices co-operating with the conducting means, and

driven means to which the piston is connected. 65

5. A cylinder for a gas turbine having a reciprocating piston provided with a compression chamber for a motive agent, ignition means comprising a tubular electrical accumulator, means for supplying current to said accumulator, a conductor movable in the accumulator and also projecting into and having fixed position in the compression chamber, the compression chamber being 70 also provided with sparking components to co-operate with the conductor, and driven means to which the piston is connected. 75

6. A cylinder for a gas turbine having a reciprocating piston provided with a compression chamber for a motive agent, ignition means comprising a movable accumulator and a movable conductor working in the accumulator and in part projecting into and having a fixed position in the compression chamber, the said chamber being also provided with sparking devices co-operating with the conductor, and driven means to which the piston is connected. 80 85

7. A cylinder for a gas turbine having a reciprocating piston provided with a compression chamber for a motive agent, the said chamber also having a motive agent receiving chamber provided with a valve having a reciprocating tubular stem, an electrical tubular conductor mounted in said valve stem, insulating means for the stem and conductor, contact devices engaging opposite portions of the conductor, electrodes 90 yieldingly engaging the contact devices and connectable to a source of electrical energy, a valve forming part of the compression chamber and having a stem with a conductor therein, the conductor being insulated 95 and having conducting means between the same and the said tubular conductor and valve stem in which the compression chamber valve stem has sliding movement, the conductor of the compression chamber valve stem projecting into and having fixed position in the compression chamber, and sparking devices also held within the compression chamber in co-operative relation to the said conductor of the compression chamber valve stem. 100 105 110 115

8. A cylinder for a gas turbine having a reciprocating piston therein provided with a compression chamber for a motive agent, said cylinder also having a motive agent receiving chamber, a valve controlling the admission of the motive agent from the receiving chamber into the cylinder, said valve being provided with a tubular stem having an electrical conducting accumulator therein also of tubular form, insulating devices 120 between the tubular accumulator and the said valve stem, contact devices engaging the said tubular accumulator, yieldingly 125

mounted electrodes engaging the contact devices, means for reciprocating the valve stem and the conducting accumulator to open and close the valve of the motive agent receiving chamber, an automatically operating compression chamber valve having 5
sparking devices fixed thereto and provided with a stem extending upwardly through the first mentioned valve into the tubular 10
conducting accumulator, and a conductor held within the stem of the valve of the compression chamber and exposed with a

reciprocating wiping action in part to the said tubular electrical accumulator to take the current from the latter and convey it 15 within the compression chamber between the said sparking devices.

In testimony whereof I have hereunto set my hand in presence of two subscribing witnesses.
